MARINE DRILLING

John R. Evans, Lloyd E. Elkins, and Louis H. Klinzing, Tulsa, Okla., assignors to Stanolind Oil and Gas Company, Tulsa, Okla., a corporation of Delaware

Application April 25, 1946, Serial No. 664,891

8 Claims. (Cl. 61—46)

1

This invention relates to marine structures and to methods for their construction and erection, and more particularly to improvements in methods and structures for deep-water drilling.

Many of the methods and structures for drilling under water, which have been employed with some success in relatively shallow water, are not adaptable to deep water. Methods employing submersible drilling barges and permanent docks constructed with piling cannot be practically adapted to drilling beneath any waters which are as much as one hundred feet or more in depth. The construction of caissons for drilling in waters of this depth is so expensive as to be prohibitive. Consequently there is great need for an efficient and practical method of drilling wells in relatively deep water in order to make the exploration and production of oil reservoirs beneath these waters commercially practicable.

One of the present methods employed is that of constructing a complete substructure which is adapted to be transported to the site and anchored on the marine floor to support a platform above the water level upon which a conventional drilling derrick and rig is mounted for carrying out drilling operations. To construct these substructures on dry land or on barges and then lower them into the water upon completion is an extremely difficult and expensive task. An alternative method that has been disclosed by the art is that of building a structure from a plurality of similar sections and assembling and welding these sections one upon the other in gradually deepening water, starting from dry land and continuing to the locality where the substructure is to be anchored. This method, however, requires towing that portion of the structure which is below the water level on skids at extremely slow speeds and with the continued risk of tipping the structure. Furthermore, considerable expensive underwater work by divers is required to anchor the structure, it is permanent and cannot be disassembled, a feature which is desirable where, as in exploratory drilling for oil or gas, the structure is useful in one locality for relatively short periods of time, and which locality may never be produced.

It is, therefore, an object of this invention to provide a method of constructing and erecting a portable marine structure for use particularly in deep water at any desired location in a simpler and more efficient manner than has heretofore been possible. It is the further object to provide an apparatus which may be so erected and particularly an apparatus which is adapted for

5 deep-water drilling and exploration of the marine floor on which it rests. It is yet a further object to provide a substructure and a method of erecting such a substructure which insures great stability during erection and upon completion of the structure against movement due to waves, winds, etc. Another object is to provide a substructure comprising a plurality of sections which can be prefabricated and then readily assembled and disassembled at the location where the structure is to be anchored, and further to provide a method and apparatus for determining the elevation of the portions of the marine floor where the structure is to be anchored so that the base section can be fabricated in accordance with conditions of the floor to insure optimum support and stability for the completed structure. Other objects and advantages will be apparent from the following description of my invention.

10 Our method of constructing and erecting a marine substructure particularly for deep-water drilling is generally that of providing a guide means, such as a guide post, extending upwardly from the marine floor toward the surface, preferably anchoring it at its base, and supporting it against sidewise movement or sway at the top, and threading on this guide means a plurality of apertured structural sections and superimposing one upon the other in such a manner as to 15 form a unitary rigid structure. The number of sections required, of course, depends upon the depth of the water, for it is preferable that the completed substructure extend out of the water to a point above the waves. The sections are 20 each similar and preferably so constructed that the assembled structure is of the skeleton type having main supports or uprights rigidly held in spaced relation by cross members and having a centrally disposed tube which slidably engages 25 the guide means and thus cooperating with the same to provide also a support for the structure against sidewise movement or sway. We further have provided interlocking means on the adjacent 30 individual sections so as to further increase the strength and stability of our substructure, even though, being of the skeleton type, it offers a minimum resistance to wave action and wind. As a further assurance of stability, particularly 35 during erection, we support the guide post at at least two vertically spaced points near the surface so that when threading the structural sections on the post during erection the post is continuously supported by detaching first one support, threading the section past this support, at

taching it again, and then detaching the second support.

As yet a further assurance of stability of our structure, we ascertain the relative elevation of the firm portions of the marine bed upon which the uprights rest and are anchored, and then construct the base section so that it will rest firmly thereon with its axis perpendicular to the surface of the water. To determine this relative elevation, we utilize as a gauge a support for a number of gauge bars which can be threaded on the guide means and lowered to the marine floor. The gauge bars are held in the same relative position in a vertical plane as that of the upright segments of the base section. The gauge bars indicate the relative elevation of the loci for the uprights when they strike solid portions of the marine floor. In order to insure that the base section assumes the same position as the gauge, it is preferable that they each be restrained from relative rotation with respect to the guide means as they are lowered.

Our marine structure can be particularly adapted to underwater drilling operations by using as the guide means means including a guide and conduit, as for example, a tube, or a plurality of tubes trussed together, which, when supported by the skeleton structure, may serve as the conducting string or strings through which the drill string operates and the well is produced. Where this is the intended result, the guide and conduit means may in some cases only be temporarily anchored until the skeleton structure is complete and in place.

The above features of this invention and others will be better understood from the following description of a preferred embodiment when read in connection with the accompanying drawings wherein like numerals indicate similar parts and wherein:

Figure 1 is a diagrammatic elevation of a marine substructure in accordance with this invention, particularly for use in supporting an oil-well derrick and complete drilling rig;

Figure 2 is a fragmentary elevation partially in section showing particularly the base section of our marine substructure and the means for anchoring it to the marine floor;

Figure 3 is a diagrammatic plan taken along the 3—3 of Figure 2;

Figure 4 is a section taken along the line 4—4 of Figure 3;

Figure 5 is a fragmentary elevation showing another modification for supporting the base section of Figure 2;

Figure 6 is an elevation partly in section of a guide means for our marine substructure during the first stages of construction and our apparatus for determining variations in the elevation of the marine floor;

Figure 7 is a fragmentary view of the apparatus shown in Figure 6;

Figure 8 is a diagrammatic elevation of an alternative embodiment of a guide and conduit means.

Our preferred substructure for oil-well drilling is a skeleton structure 1 of frustro-pyramidal shape having mounted thereon a conventional oil-well derrick 2 supported on a deck 3 from which oil-well drilling operations can be conducted in the marine floor 4 beneath the substructure. The substructure as shown comprises four main supporting uprights 5, preferably hollow or tubular, which are rigidly held by braces, such as horizontal cross members 6 and diagonal

cross members 7. Centrally disposed within the area defined by the uprights 5 is a tube 8 rigidly supported by the uprights through radial braces 9 (Figure 3). Within the tube 8 is disposed a vertical guide means or column 10, preferably tubular, anchored on the marine floor at its base 11 and supported against lateral movement or sway preferably near the top by buoyant means or, for example, by two spaced supports or detachable split collars 12 and 13 (Figure 6). Guy wires 14 and 15, which are anchored by naval anchors 18 (only one shown) at spaced points substantially removed from the base of the substructure, are secured to these detachable split collars 12 and 13, respectively.

The skeleton structure 1 is formed of a plurality of similar independent frustro-pyramidal sections of skeleton formation, as for example, base section 20, the next adjacent section 21, etc., 20 which are superimposed one upon the other and each including tubular uprights 22, a vertical tube 23, the horizontal cross members 6, diagonal cross members 7, and radial braces 9. The tubular uprights 22 and vertical tube 23 of each section 25 are segments making up the continuous main supporting uprights 5 and centrally disposed tube 8, respectively. Each of these sections is interlocked with respect to each other by a dowel 24 and a socket 25 on the abutting ends 30 of the segments of the tubular uprights 22 (Figure 4). This interlocking of each section adds to the rigidity of the entire structure against lateral movement or sway. In some instances, interlocking against vertical movement or 35 placement may be obtained by a latch, such as a pawl and stop, but in general the weight of the sections is sufficient.

In erecting the marine substructure of Figure 1, the vertical column 10 is lowered to the marine floor at the desired location and temporarily anchored by prongs or teeth 26 at the base thereof which tend to penetrate mud or sand on the marine floor and secure a firm footing for the column. The upper end of the column, which preferably extends above the water level, is then supported against lateral movement or sway by the guy wires 14 and 15. The collars to which the guy wires are attached are secured to the column 10 at points vertically spaced a distance at least as great as the height of any one section 45 for reasons hereinafter set forth. The vertical column may be permanently anchored to the main floor with hydraulic cement as by a cement plug 28 reinforced with a tube 29 or drill rod extending through a part or all of the column 10 55 and into a hole 30 beneath the column. This hole can readily be made by passing a rotary drill down through the column.

By using a tubular column we not only have 60 provided guiding means, but also have provided conduit means permitting the use of this advantageous method of anchoring, as well as a conducting string through which the drilling may be accomplished and the well produced in those 65 instances where the substructure is used for drilling wells. In these cases in which the substructure is used for drilling wells, the well may be drilled from any position within the confines of the substructure but preferably the reinforcing tube 29 used in anchoring may be selected of a sufficiently large diameter to receive the drill bit and thus serve as the well casing. In some cases 70 wherein the substructure is used for drilling, the column 10 alone may serve as the casing, either anchored in cement or merely anchored by the

teeth 26. In some instances it is desirable to provide latch means between the vertical tubes 23 so that the substructure will be more rigid and resist lateral forces, especially when the column is to serve as a casing.

After the vertical column 10 is in place, it is then desirable to ascertain the elevation of those portions of the marine floor which will serve as the bearing surfaces for the four main supporting uprights 5. This may be done by threading on and lowering onto the column 10 a disk-shaped gauge support 31 (Figure 6) having a centrally disposed bearing or guide 32. Slidably disposed within suitable sockets 33 on the gauge support are gauge bars 34 which are positioned to contact the marine floor at those points where the uprights of the base section will contact it when in position. The gauge bars are so fitted in the sockets that they are frictionally held normally extended until they penetrate mud and sand and strike consolidated rocks or sediments in the marine floor whereupon they slide upwardly relative to the support as it is lowered to the base of the vertical column to the position shown. The friction between sockets 33 and gauge bars 34 is maintained sufficiently high so that the final position of the gauge bars in the gauge support will be retained when the gauge support is withdrawn, indicating thereby the relative elevations of the contact portions of the floor.

It is an important feature of our method of erection that when the gauge support 31 and any of the skeleton structure sections are threaded onto the column, only one of the lateral supports to column 10 is disconnected at any time; i. e., the top support is first detached by opening the split collar 12 while the bottom support holds the column against lateral movement as the gauge support or section is lowered on the column to a point between the split collars 12 and 13. The top support is then attached to the column before the lower support is detached. Lastly, the lower support is removed from the column to permit the gauge support or section to be lowered to the marine floor. In this manner the column is continuously supported to resist lateral forces which might otherwise under most circumstances cause the column to fall during the time the structure is under construction. The gauge support is lifted over the column, threaded, and lowered thereon by suitable hoists (not shown) mounted on working barges in any conventional manner.

Having thus ascertained the relative elevation of the portions of the marine floor which will support the structure, the base section 20 of the structure is constructed, preferably on the barge from which the construction crew works, with the uprights 22 extended forming legs 35 of proper length to rest on the marine floor and maintain the axis of the base section vertical. Another method of doing this is to have the uprights of the base section include hydraulic expansion joints whereby each could be preset to the desired length. Such joints may also, in some circumstances, be included in the other sections in order to level them. This base structure is lifted over and threaded onto the column in the same manner as the gauge support and lowered by the hoist into position. In order to insure that the base section is in the same azimuthal position or alignment with respect to the marine floor as the gauge support, suitable splines or keys 36 are provided on the column. Corresponding keyways 37 are likewise provided within the bearing or

guide 32 of the gauge support and within the centrally disposed tube 23 of the base section 20. This same method is followed for restraining relative rotation and for securing alignment of each of the upper interlocking sections.

After the base section 20 is in place, the next section 21 is then threaded onto the column after detaching and attaching the respective detachable split collars 12 and 13 and lowered into position on the base section. The sections are interlocked by the dowels 24 and sockets 25 which automatically engage because of the alignment of the sections. These steps are repeated until a sufficient number of sections have been positioned to bring the structure to the required height above the water level. This height may vary depending upon the wave and wind conditions in the particular region.

After the skeleton structure is built up, each of the four uprights 5 may be anchored to the marine floor in the same manner as the column 10: i. e., by drilling holes 38 beneath them and cementing into these holes and uprights a drill pipe 38a to obtain maximum strength and stability. The uprights 5 should, particularly in a permanent erection, preferably be cemented or anchored throughout their entire length, for in this way each and all of the sections are anchored relative to the marine bed and to each other. Where, however, the substructure is to be used temporarily, as for example, for exploratory drilling, it is preferable to anchor or cement only the base section or in some case use no anchor of a permanent nature, so that each of the free sections may be readily raised off the vertical column 10 and the substructure thus disassembled. In this regard, although each of the sections may be partially buoyant, it is understood that they are sufficiently heavy to remain in place and rest on each other. It may be desirable to make the buoyancy of the sections increase with their position in the structure, i. e., the lower the section the more buoyant, since the accumulative weight of those above will insure stability, yet the entire column will bear less heavily on the marine floor and hence be less likely to cant. Where necessary to obtain footing on relatively soft bottoms, feet 39 (Figure 5) may be provided. These may comprise a plurality of disks 40 welded or otherwise connected to the lower ends of uprights 5.

After the substructure is completed and anchored, the drilling derrick 2 and an extended conventional derrick substructure, such as the dock 3, may be constructed thereon and drilling equipment mounted. Thus it is apparent that our marine structure may be constructed without any expensive underwater work by divers and is capable of being readily dismounted where desirable.

From the above description it is apparent that the vertical column 10 has the primary function of serving as a guide or guide means during the lowering of the sections comprising the skeleton structure to their proper location. For this purpose, therefore, the vertical column may comprise any preferably rigid, or in some cases flexible, shaft, tube, or other structural element of any suitably shaped, substantially uniform cross section. Where, for example, the substructure is to be placed in extremely deep water so that a single casing of as much as 20 to 24 inches in diameter may not have sufficient strength, the guide means may comprise, for example, a trussed structure 41 (Figure 8), including a central tube 42 and upright members 43 forming externally guiding surfaces connected by braces

44, 45, and 46. A vertical column or guide post of this type may also include, where it is desired to drill a plurality of wells, as an integral part thereof, a plurality of pipes 47 suitably supported by the braces 44, which may serve as conductor strings for a number of different wells to be drilled from the structure. In this embodiment the central tube 42 may be permanently anchored with cement as described above.

The above description of a preferred example of our marine substructure and method of constructing and erecting the same is given by way of illustration and many modifications and variations will occur to those skilled in the art. Therefore, no limitations are intended by the above description except as are contained in the following claims.

We claim:

1. A marine substructure comprising a vertical column, means for anchoring said vertical column in the marine floor, means supporting said column against lateral movement or sway, and a frustro-pyramidal skeleton structure including supporting uprights and a centrally disposed axial tube disposed around said vertical column, said tube and said uprights being held in rigid spaced relation by braces.

2. A marine substructure comprising a guide column, means for anchoring said guide column in the marine floor, means for supporting said guide column in a substantially vertical position, and a plurality of structural sections having a centrally disposed aperture threaded on said guide column and superimposed one upon the other, all said sections forming a rigid elongated structure.

3. The marine substructure of claim 2 wherein said means supporting said guide column comprises at least two sets of guy wires detachably secured at vertically spaced points to said guide column at one end and anchored in the marine floor at the other end.

4. A marine substructure for well drilling comprising a plurality of structural sections of skeleton formation superimposed one upon the other, each of said sections including hollow uprights and an axial tube, said uprights and said tube being held in rigid spaced relation by braces and said uprights and said tube of each of said sections being in substantial alignment, forming thereby continuous hollow uprights and a continuous tube extending from the marine floor to above the water level, a vertical tubular column disposed within said continuous tube and extending from the marine floor to a point above the top of said tube, means for anchoring said column in the marine floor, means to support said column against lateral movement, and means disposed throughout each of said continuous hollow uprights and in said marine floor for anchoring each of said sections relative to said marine floor.

5. The marine substructure according to claim 2 which comprises cooperating surfaces on said guide column and the centrally disposed aperture of said structural section adapted to prevent relative rotation between said guide column and said structural section.

6. A marine substructure comprising a plurality of superimposed rigid frustro-pyramidal sections of non-buoyant construction, each of said sections including a centrally disposed tube and non-coaxial upright supports, said centrally disposed tube being held in rigid spaced relation to said uprights by braces and all of said superimposed sections forming together a rigid elongated structure having a continuous centrally disposed tube in spaced relation to the uprights of said structure, and a tubular column disposed within said central tube and extending from the marine floor to above the upper end of said elongated structure.

7. A frustro-pyramidal section for a marine substructure comprising a centrally disposed guide tube, upright supports held in spaced relation to said tube by braces, the length of the component of said upright supports parallel to the axis of said tube being substantially equal, interlocking dowel means at the ends of said upright supports to connect to the ends of similar supports of other frustro-pyramidal sections, and spline means in said tube adapted to cooperate with a guide member to orient said section, whereby said upright supports will be aligned with and will engage supports of other frustro-pyramidal sections when they are lowered on said guide member and whereby a minimum of underwater work by divers is required to assemble a number of such sections and to erect a marine substructure.

8. In the process of erecting a marine substructure having a multiplicity of spaced supporting uprights on an uneven marine floor, the steps of setting on said floor a guide column which extends above the water level, supporting said guide column against lateral movement, threading onto said guide column a gauge support having gauge bars in spaced relation and oriented to correspond to the proposed position of said uprights, said gauge bars being movable vertically relative to said gauge support, lowering the gauge support until the vertical position of said gauge bars corresponds to the elevation of the floor at the proposed position of said uprights, and retrieving said gauge support whereby said substructure can be prefabricated to stand erect on said uneven marine floor before said substructure is lowered to said floor.
